CYLINDER HEAD FOR INTERNAL COMBUSTION ENGINES

Alfred Schwarz, Montclair, N. J., assignor to The Economy Engineering Corporation, New York, N. Y., a corporation of Delaware

Application December 21, 1934, Serial No. 758,596
Renewed March 12, 1938

8 Claims. (Cl. 123—173)

This invention relates to improvements in cylinder heads for internal combustion engines, and is a continuation in part of my co-pending application Ser. No. 680,635 filed July 14, 1933.

5 In my earlier application aforesaid, I have described the advantages of forming the combustion chamber of an internal combustion engine by means of a cylinder head in which the metal distribution is pre-calculated so that the temperature of various portions of the combustion chamber will, after compression, be substantially uniform and avoid overheating a portion of the charge and thereby cause its too early decomposition and therefore prevent what has come to be 10 known as detonation.

In the operation of an internal combustion engine it requires but a fraction of a second to perform the functions of compressing the charge and exploding the same in a cylinder and it is 15 therefore of great importance to have the charge properly prepared or conditioned, so to speak, or in other words, to have the same present in the cylinder under the most favorable conditions at the time of its ignition and combustion.

20 Apparently the best conditions exist when the charge is present in the cylinder in a highly compressed condition and properly heated, by both compression and other means.

It is well known that there is a critical temperature at which each fuel will automatically 25 ignite and that the fuel-air mixture should be present in the cylinder in a highly compressed state, and that the temperature thereof should be uniform throughout the compressed charge.

30 Moreover, this compression-end temperature, so to speak, should be close to but slightly below the critical temperature, known as the auto-ignition temperature. When the charge is properly prepared, it may be electrically ignited and com-

35 bustion will take place at a rate of flame propagation proportional to the temperature of the charge and bear a relation to the amount of its compression at the time it was ignited. If interior portions of the cylinder head have different tem-

40 peratures due to operating conditions, a variable heat transfer would take place between the charge and its confining walls and the hotter portions of the charge would burn faster and the cooler portions burn slower. Such burning ir- 45 regularities manifest themselves in what is referred to above as detonation. Such detonation results in an uneconomical operation of the engine.

An object of the invention, therefore, is to pro- 50 vide means, in addition to those described in the

previous patent application, for forming a combustion chamber having a substantially uniform interior wall temperature, which wall temperature should bear a relation to the compression ratio.

5 In the past when water cooled cylinder heads were molded from cast iron or other metals, it was necessary to make the thickness of the wall forming the combustion chamber sufficient to permit the hot metal to flow through such molds 10 and therefore the wall thickness was not limited by the temperature requirements of the combustion chamber but by the requirements of the method of manufacture. Furthermore, bosses had to be provided for the spark plug, the stud 15 bolts, water connections, timer shafts, etc., and when they were located near the combustion chamber the metal of the bosses was necessarily integral with that of the walls of the combustion chamber and incidentally placed quantities of metal near the combustion chamber walls which are capable of absorbing heat, and which, during the operation of the engine, became, in effect, hot spots capable of pre-igniting the charge 20 and causing detonation.

25 I have also found that it is difficult to cast cylinder heads having cored water jackets and at the same time make the walls of the combustion chamber defining the different portions thereof of the proper cross-sectional thicknesses 30 to bring about a balanced temperature effect. One reason for this difficulty in making cast cylinder heads as heretofore, is that the cores for forming the water jacket often become shifted or mutilated during the molding and casting 35 operation, and result in more or less indeterminate wall thicknesses. Accordingly, it is desirable to construct a cylinder head so that the combustion chamber walls may be machined to the proper thickness, if necessary, after the cast- 40 ing operation.

45 Prior to my invention, which teaches the importance of balancing the temperature in the combustion chamber, so to speak, no particular attention was paid to the location of this excess, or what, for the want of a better name, I shall describe as parasite metal, or the variations in the cross-sectional thickness of the combustion chamber wall. I have discovered, however, by the aid of thermo-couples applied during power 50 tests, that temperature differences of from 100° to 200° F. are often present within a small combustion chamber, and that when such parasite metal was properly removed, and the temperature of various portions of the head equalized, an in- 55

creased horse power output was obtained often as high as 20% to 30%. This is due to the fact that higher compression ratios are permissible, together with earlier spark settings, and the explanation for this new technical effect resides in the fact that faster and slower burning results respectively from hotter and colder portions of the charge. If the entire charge is of a correct temperature, except for one small portion which is at a higher temperature, then this will prevent the use of a higher compression ratio, because the hot spot will then pre-ignite the charge.

An important object of my invention, therefore is the production of an improved cylinder head comprising a chamber or water jacket formed about a cast head plate by means of a pressed steel top or cover for said plate having the edges thereof crimped beneath the edge of the plate, or otherwise suitably secured thereto.

Another object of my present invention is the production of a combustion chamber, in which different portions of the walls thereof are of different and predetermined thicknesses, and to devise means to attach such combustion chamber to the cylinder block of the engine without having the heat transfer, or a heat retention, from the walls or construction members of the combustion chamber disturb the heat balance in said chamber.

Other objects and advantages of my invention will become apparent or be specifically referred to in the following description thereof taken in connection with the accompanying drawings, in which:

Figure 1 illustrates a cross-sectional assembly view of my improved heat balanced cylinder head mounted on the cylinder block on an internal combustion engine. The view of the head plate in this figure is taken on line 1—1 of Figure 2.

Figures 2, 3 and 4 illustrate top plan, sectional and bottom plan views, respectively, of the cylinder head plate shown in Figure 1.

Figure 5 shows a sheet metal stamping, which may be described as an inverted pan-like structure adapted to form with the head plate, a water jacket over the entire cylinder head when the same is assembled thereon.

Figure 6 is an inverted diagrammatic view of one manner of bending and forming the edges of the jacket stamping under the edges of the head plate.

Figure 7 illustrates a modified form of my assembled water jacket in which the head plate is confined in a sheet metal casing, which casing comprises a flat perforated plate and a water jacket welded together at the periphery thereof.

Referring now to the drawings, it will be seen that Figure 1 illustrates a fragmentary cross-sectional view of a common type of L-head engine equipped with my improved cylinder head. This engine comprises a cylinder 1, a piston 2, a space 3 about the cylinder, through which cooling water may be circulated, and a cylinder head 4 (not numbered) comprising a head plate 5 and cover 6 forming a space 7 above the plate 5 through which cooling water is circulated through the assembled head. The cover 6 is made from a sheet metal stamping having a skirt or side walls 8 disposed around the periphery thereof, as shown in Figure 5, and adapted to be assembled on the head plate by forming the lower edge of the walls 8 under the edge of the head plate 5.

A bead or shoulder 9 is preferably formed

around the edge of the head plate 5 and the skirt is crimped about this bead by means of forming dies 10 and 11, see Figure 6. By constructing the head plate with a bead of this type, the forming dies may be made with a clearance 12 at the bottom (top in Fig. 6) and may be otherwise adapted to exert their forming pressures on either side of the bead rather than subjecting the stud bosses 13 thereto. The head is secured to the cylinder block in the usual way by stay bolts 14. It will be understood that a gasket 15 is interposed between the cylinder block and head, in the usual way and that sealing washers 16 are disposed under the heads of each of the stay bolts 14. Finally the edge 17 of the spark plug hole 18 is rolled into a recess provided in the head plate 5. When the head plate 5 and cover 6 are assembled as described, no attempt is made to seal the cover to the head, because this is done solely by clamping the head plate to the cylinder block between the gasket 15 and washers 16. It will be particularly noted that the turned under portion of the cover 6 fits in a recess 19, see Fig. 3, formed in the face of the head plate and that the edge 17 of the cover extends far enough into this recess and under the edge of the head plate 5 to be effectively sealed thereto when the assembly is clamped by the studs 14 to the block.

Figure 1 also illustrates an intake port 1, and an intake valve V, which is operated during the engine cycle by any suitable means, as is the exhaust valve, not shown, although preferably located proximate thereto.

Figure 1 further illustrates a combustion chamber formed above the cylinder by the head plate 5. This chamber comprises a large volume portion 20 extending over both the intake and exhaust valves and over a small sector portion 21 of the piston area, see Figure 4. The small volume portion of the chamber includes a thin, flat crescent-shaped space 22 overlying most of the piston area which is closely confronted by the cooled wall 23 of the head. In an ordinary engine of this type having a four to one compression ratio, the large space 20—21 may contain approximately 85% of the combustion chamber volume, while the thin crescent-shaped space 22 may contain 15% or less. If Figure 1 illustrated a cast iron cylinder head as ordinarily constructed, that is, with a combustion chamber wall of uniform cross-section throughout, it would be found that the lower surface of the head wall proximate the crescent-shaped space 22 would be one of the best cooled surfaces of the head, notwithstanding the amount of heat in the volume of the charge in contact therewith is relatively small when the piston is at upper dead center. Operating at a compression ratio of five to one with the jacket water at 150° F. the cooling surface adjacent the crescent 22 of the combustion chamber was about 300° F. The temperature variations in other portions of the combustion chamber were approximately as follows: namely, the exhaust valve was about 900° F.; the cylinder block surface adjacent the exhaust valve was about 700° F.; the head wall over the exhaust valve was about 600° F.; the intake valve was about 250° F.; the surface of the head block adjacent the intake valve was about 275° F. and the surface over the intake somewhat higher.

Bearing in mind that the heating due to compression by the piston is precisely the same for all of the charge, and that in this case the normal

compression temperature was about 525° F., it will be evident that when the piston is at the upper dead center the part of the charge in the region near the intake and above the lines A—B, see 5 Figure 4, and in the crescent space 22 over the piston, will be much cooler than in the region below the line A—B which is near the hot exhaust valve.

In this type of engine, ignition is effected near 10 the center of the large volume cavity 20 on the upper or cooler side of the line A—B. Consequently, this part of the charge is partly taken care of because most of it is burned by the time its 15 radiant heat and pressure have been able to produce high pressures and temperatures in the remaining parts of the charge.

In the above case where the compression ratio was five to one, I found that under normal operating conditions the part of the charge in the region 20 below the line A—B was raised from its normal compression temperature of 525° F. up to 600° F., while the average charge temperature of the section above the line A—B was lowered to 400° F. so that there was a general temperature differential 25 of 200° F. which favored secondary decomposition of the fuel and detonation. Of course the actual charge temperature cannot be determined as accurately as the wall temperatures and it is obvious that with the above general differential 30 of approximately 200° F., for the two characteristically different regions of the charge, there are certain parts of the charge in each region in which the local charge temperatures are respectively higher and lower than those indicated above.

In Figure 1 I have shown more or less diagrammatically how a practical approximation of uniformity of charge temperature may be obtained by a very simple means. In this case the crescent-shaped wall at 23, see also Fig. 4, defining the 40 thin compression space above the piston, has been made much thicker than heretofore to decrease the dissipation, by the cooling means, of the heat at this point, and enable the thickened walls to actually store up more heat than heretofore, and 45 thereby elevate the temperature of the charge in that part of the combustion chamber which has heretofore been comparatively cool. As stated in my copending application Serial No. 680,365, and above referred to, the thickness of the wall portion 50 23 overlying the engine cylinder region may be .58 inch, the thickness of the wall portion 24 overlying the exhaust valve region may be .195 inch, and the thickness of the wall portion overlying the intake valve region of the combustion 55 chamber may be .23 inch. Therefore the wall portion 24 over the generally hotter section of the compressed charge, due to the heat from the exhaust valve (not shown) and surrounding parts, has been made thinner than the wall portion 60 over the laterally adjacent intake valve region to promote the dissipation by the cooling means of the heat from this portion 24 of the combustion chamber, as is also indicated in Figs. 2 and 3. In this way I have been able to equalize the temperatures of the combustion chamber by decreasing the cooling effect of the medium upon the walls defining the normally cooler regions of the chamber and increasing the cooling effect of the medium upon the walls defining the hotter regions of the chamber whereby to balance the wall temperatures of the combustion chamber for the 65 reasons above set forth.

If it be assumed that Figure 1 illustrates a 70 properly prepared compressed charge in the com-

bustion chamber 20—21—22 and this charge is ignited by spark plug 25 then the flame propagation will begin at the spark plug and progress through the compressed charge and strike the surface 26 of the combustion chamber with great 5 severity because it is at approximately the point 26 that the burning charge is caused to suddenly change its course and be directed downwardly into the cylinder. I have discovered that this point 26 is probably the hottest section of the 10 combustion chamber wall, and for that reason I have made the wall section at this point thinner than at any other section by providing a depression 27 in the head plate to bring the cooling water as close to the point 26 as practicable 15 possible.

From the above it will be seen that the wall 20 temperatures of my combustion chamber are, by the expedient described, heat balanced, so to speak, to prevent the residual heat in certain sections from too early igniting said sections of the compressed charge and prevent other sections from cooling portions of the compressed charge before it is ignited.

I have pointed out above that in making cast 25 iron cylinder heads, the molding technique may often require wall thicknesses in excess of those properly adapted to promote a balanced temperature for the walls of the finished combustion chamber. Accordingly, it becomes important to 30 be able, when the combustion chamber walls cannot be cast of the proper thickness originally, to cast them heavier than need be, and thereafter machine them to the desired thickness. This 35 necessarily requires the construction of a cylinder head in such a manner that one can machine the surfaces over which the cooling medium is to come in contact after the head plate has been cast. Broadly speaking, my invention comprises, 40 in addition to the means for balancing the wall temperatures of the combustion chamber, means for constructing what may be described as an assembled water jacket, as distinguished from one cast, as is so common in present day practice, 45 integral with the cylinder head forming the combustion chamber.

Referring now to Figure 7, wherein I show a modified form of water jacket, it will be seen that the head plate 5 is confined between a cover 40 and a flat suitably perforated metal plate 41. 50 In this structure, an outwardly extending flange 42 is formed about the cover 40 and welded in any suitable manner to the edge of the plate 41 after the head plate 5 is disposed therebetween. A gasket 43 is employed in the usual way and for 55 the usual purpose between the assembled head and cylinder block 44. It will be understood that the perforations referred to in the plate 41 conform and register with those in the gasket 43. The modification shown in Figure 7 also illustrates that the head 5 is coated at 45 with a specially selected insulating material comprising a binder and a filler. I prefer to use asphalt as a binder and graphite as a filler and the purpose of this coating is to regulate or further control the 60 heat flow from the combustion chamber into the water jacket. The thickness of this coating is approximately that of a paint coat. In cases where it is desired to greatly retard or insulate the heat flow, a siliceous material may be used, such as cement, fuller's earth, or ground quartz. The function of the coating is to retain in the cylinder head the proper amount of heat and be able to do so without making the casting thicker than neces- 65 70 75

sary for structural considerations. I have found, therefore, that it is cheaper to make a thin casting, although one which is strong enough for structural purposes, but which would not of itself have the proper heat retention qualities, and supply those qualities to the casting by means of the coating.

Attention is also directed to the modified manner of sealing the water jacket to the spark plug bosses. In the form shown in Figure 1, wherein the edge 17 is expanded into a recess formed in the top of the spark plug boss, it has at times been found that certain materials may be cracked during the expansion operation. In Figure 7, however, the corresponding edge 48 of the cover 40 is clamped by the spark plug to the top of the boss and the water jacket sealed at this point, to a finished circumferential surface 49 formed on the boss, by being pressed over the top thereof. A depression 50 is formed in the water jacket about the boss to prevent the normal expansion and contraction of the metal from breaking the seal at this point.

Attention is also directed to a further modification in the form of the water jacket shown in Figure 7 in that it is formed with an offset 51 to reduce the volume of water disposed over the normally cooler portion of the head which tends to elevate the temperature thereof. In other words, the reduced quantity of cooling water, available at the right-hand edge of the head plate shown in Figure 7 over the thick wall 23, tends to further decrease the dissipation of heat from this section of the combustion chamber.

While I have described what seems now to be the preferred embodiments of my invention, it is conceivable that various modifications in the configuration, composition and disposition of the component elements which make up my invention as a whole, as well as in the selective combination and application of the respective elements, may occur to those skilled in the art, and no limitation is intended by the phraseology of the foregoing description or illustrations in the accompanying drawings.

What is claimed is:

1. An internal combustion engine having a head with water cooled walls defining a combustion chamber in proximity to intake valve means which normally tends to maintain the adjacent wall at a relatively low temperature, and exhaust valve means which normally tends to maintain the adjacent wall at a relatively high temperature, the thickness of that portion of said wall in proximity to said intake valve means being relatively thick and the thickness of that portion of said wall in proximity to said exhaust valve means being relatively thin, whereby uniform combustion wall temperature during the power stroke of the engine is maintained.

2. An internal combustion engine having a head with water cooled walls defining a combustion chamber in proximity to intake valve means and a cylinder portion, both of which normally tend to maintain the adjacent wall at a relatively low temperature, and exhaust valve means which normally tends to maintain the adjacent wall at a relatively high temperature, the thickness of that portion of said wall in proximity to said intake valve means and cylinder portion being relatively thick and the thickness of that portion of said wall in proximity to said exhaust valve means being relatively thin, whereby uniform combustion wall temperature during the power stroke of the engine is maintained.

3. A head for an internal combustion engine cylinder block, said head having a combustion chamber forming wall overlying the cylinder and the intake and exhaust valve ports for said cylinder in said block, said wall being divided into areas of differential heat transfer capacity, the area of great heat transfer capacity overlying the exhaust port region of the block and the areas of lesser heat transfer capacity overlying the intake port and cylinder regions of the block, whereby uniform combustion wall temperature during the power stroke of the engine is maintained.

4. A head for an internal combustion engine cylinder block, said head having a combustion chamber forming wall overlying the cylinder and the intake and exhaust valve ports for said cylinder in said block, said wall being divided into areas of differential heat transfer capacity, the areas of lesser heat transfer capacity overlying the intake port and cylinder regions of the block, and an angularly positioned relatively small region of greater heat transfer capacity joining the areas overlying the intake port and cylinder regions of the block, whereby uniform combustion wall temperature during the power stroke of the engine is maintained.

5. A head for an internal combustion engine cylinder block, said head having a combustion chamber forming wall overlying the cylinder and the intake and exhaust valve ports for said cylinder in said block, said wall being divided into areas of differential heat transfer capacity, the area of minimum heat transfer capacity overlying the cylinder region, the area of maximum heat transfer capacity overlying the exhaust port region and the area of intermediate heat transfer capacity overlying the intake port area of the block, whereby uniform combustion wall temperature during the power stroke of the engine is maintained.

6. A head for an internal combustion engine cylinder block, said head having a combustion chamber forming wall overlying the cylinder and intake and exhaust valve ports for said cylinder in said block, said wall being divided into areas of differential heat transfer capacity, the area of minimum heat transfer capacity overlying the cylinder region, the area of maximum heat transfer capacity overlying the exhaust port region, and the area of intermediate heat transfer capacity overlying the intake port area and extending a substantial distance over the center of the cylinder region, whereby combustion wall temperature during the power stroke of the engine is maintained.

7. A head for an internal combustion engine cylinder block, said head having a combustion chamber forming wall overlying the cylinder and intake and exhaust valve ports for said cylinder in said block, said wall being divided into areas of heat transfer capacity, the area of minimum heat transfer capacity overlying the cylinder region, the area of great heat transfer capacity overlying the exhaust port region, and the area of intermediate heat transfer capacity overlying the intake port area and extending a substantial distance over the center of the cylinder region, and an angularly positioned relatively small region of maximum heat transfer capacity adjoining the areas overlying the intake port and cylinder regions of the block, whereby uniform combustion wall temperature during the power stroke of the engine is maintained.

8. A head for an internal combustion engine
